UNITED STATES PATENT OFFICE.

FRANK SWALES, OF LONDON, ENGLAND.

DESIGN FOR A CURB-HOOK.

SPECIFICATION forming part of Design No. 32,896, dated July 3, 1900.

Application filed May 29, 1900. Serial No. 18,467. Term of patent 14 years.

To all whom it may concern:

Be it known that I, FRANK SWALES, a subject of the Queen of Great Britain, and a resident of London, England, have invented and produced a new and original Design for Curb-Hooks, of which the following is a specification, reference being had to the accompanying drawings, forming part thereof.

Referring to the drawings, Figure 1 is a perspective view of my new design, and Fig. 2 is a central longitudinal section through the same.

The leading feature of my design consists of a central portion A, which is circular, forming, substantially, a circle or ring-center, with the inner and outer edges rounded, as shown in the drawings. Extending from the lower portion of the circle A is an arm C, bent first lightly downwardly, as at c, and then curved

upwardly substantially parallel with the face 20 of the circle A to about the center of the same, when the free end c' of said arm C is formed inwardly and downwardly within the aperture a of the said circle A. The upper arm B is formed into a rounded portion b, and 25 the edges of both the arms B and C are slightly rounded.

Having thus described my invention, what I claim, and desire to secure by Letters Patent, is—

The design for curb-hook substantially as herein shown and described.

In witness whereof I have hereunto set my hand this 4th day of May, A. D. 1900.

FRANK SWALES.

In presence of—

HORACE PETTIT,
E. A. PAUL.
